UNITED STATES PATENT OFFICE.

ANDREW J. BURKE, OF ELM GROVE, ILLINOIS.

WAGON-JACK.

SPECIFICATION forming part of Letters Patent No. 288,772, dated November 20, 1883.

Application filed September 12, 1883. (No model.)

To all whom it may concern:

Be it known that I, ANDREW J. BURKE, of Elm Grove, in the county of Adams and State of Illinois, have invented a new and Improved Wagon-Jack, of which the following is a full, clear, and exact description.

The object of my invention is to provide a new and improved jack for raising a wagon-axle, which jack is provided with means for locking it in place when the axle is raised to any desired height, from one to six inches.

The invention consists in a wagon-jack constructed with a lever for raising the axle, to which lever another lever is pivoted and pressed from the same by a spring, a pin with a head passing from the axle-raising lever through the lever pressed upward by the spring. Two levers are pivoted to the standard, and are united at their free ends by a pintle passing above the axle-raising lever and its spring-lever, the cross-pintle being adapted to catch on the headed pin and hold one end of the axle-raising lever in the lowered position.

Reference is to be had to the accompanying drawings, forming a part of this specification, in which similar letters of reference indicate corresponding parts in all the figures.

Figure 1 is a longitudinal elevation of my improved wagon-jack, parts being broken out and others shown in section. Fig. 2 is a plan view of the same. Fig. 3 is a side of part of a modification.

The lever A is pivoted, by means of a pintle, a, to standards B, secured to a base, C, the said standards being provided with a series of apertures, b, for the pintle a, to permit adjusting the lever A higher or lower. That end of the lever which supports the axle 40 D is slightly recessed or hollowed out. A lever, E, is pivoted on the lever A at the pivoted end, and is pressed upward by a spiral spring, F, surrounding a pin, G, projecting upward from the free end of the lever A, and 45 passing through an aperture in the free end of the lever E, which pin G has a head, H, above the lever E. Guide-pins K project from the lever A through apertures in the lever E.

In place of the spring F surrounding the pin G, springs L can be fastened to the side edges of the levers E and G.

Two levers, M, pivoted by a pintle, g, to the sides of the standards B, are united at the free ends by a cross-pin, N, above the lever E. 55 The standards B are provided with a series of apertures, d, to permit pivoting the levers M higher or lower, as may be necessary. A spring, O, has one end mounted on the pintle g, and the other end bears against the bottom 60 edge of the lever A. Between its ends the spring passes over a pintle or bolt, P, uniting the levers M.

The jack is used in the following manner: The recessed end of the lever A is placed under the axle D and the other end is pressed downward, whereby the axle will be raised. After the cross-pin N has passed the pin G the free end of the lever E is pressed toward the lever A. The spring O presses the free 70 ends of the levers M in the direction of the arrow a'. The lever E is pressed by its spring against the pintle N, and thus holds the same against the pin G and its head. The head H prevents the lever E from pressing the pintle 75 N above the upper end of the pin G. The levers M can thus hold one end of the lever A lowered and the other end and the axle on the same raised.

Having thus fully described my invention, 80 I claim as new and desire to secure by Letters Patent—

1. In a wagon-jack, the combination, with a standard, of a lever for raising the axle, pivoted on the same, and two levers pivoted to 85 the standard and united at the free ends by a pintle passing over the lever for raising the axle, and over a lever pivoted on the lever for holding the axle, and pressed upward from the same by a spring, substantially as herein 90 shown and described.

2. In a wagon-jack, the combination, with a standard, of a lever, A, pivoted to the same, the lever E, pivoted to the lever A, a spring for pressing the lever E from the lever A, the pin 95 G, provided with a head, H, and the levers M, pivoted to the standards and having the free ends united by a pintle, N, substantially as herein shown and described.

3. In a wagon-jack, the combination, with 100 a standard, of the lever A, pivoted to the same, the lever E, pivoted to the lever A, a spring for pressing the free end of the lever E from the lever A, the pin G, having a head, H, the le-

vers M, pivoted to the standard, and having the free ends united by a pintle, N, and the spring O, substantially as herein shown and described.

5. 4. In a wagon-jack, the combination, with a standard, of the lever A, pivoted to the same, the lever E, pivoted to the lever A, a spring for pressing the lever E from the lever A, the guide-pins K, the pin G, having a head, H,

the levers M, pivoted to the standard, and to having the free end united by a pin, N, and the spring O, substantially as herein shown and described.

A. J. BURKE.
